UNITED STATES PATENT OFFICE.

JEREMIAH N. BULL, OF SPRINGFIELD, MASSACHUSETTS.

DESIGN FOR A HALTER-LOOP.

SPECIFICATION forming part of Design No. 23,064, dated February 13, 1894.

Application filed December 14, 1893. Serial No. 493,713. Term of patent 7 years.

To all whom it may concern:

Be it known that I, JEREMIAH N. BULL, a citizen of the United States of America, residing in Springfield, in the county of Hampden and State of Massachusetts, have invented and produced a new and original Design for a Halter-Loop, of which the following is a specification, reference being had to the accompanying drawing, forming a part thereof.

10 In the drawing I illustrate my design for a halter loop.

The leading feature of my design consists in a substantially rectangularly shaped loop formed by four bars convex upon their outer 15 surface and having interior cross bars extending at the top from side to side of the rectangular frame and from the inner bar downwardly to the base of the loop and having arranged at one of the lower corners of the rectangular frame a ring or loop rounded on both 20 sides and connected with the frame by a rounded neck.

The letters *a a* designate two parallel bars forming a part of the frame, and the letters *b b* indicate the lower and upper bars, the latter forming the ends of the frame, and the

former the sides. These bars are united and are provided with rounded corners. The neck *d* is secured to the frame at the corner formed by the junction of the bar *b* with one 30 of the side bars and projects at an angle of about forty-five degrees, and a ring *e* which is attached to the neck.

The inner face of the loop consists of the bar *j* arranged at a short distance from the 35 inner face of the frame, and with its ends bent downwardly in curved lines to meet and join said frame. The bar *f* extends from the central portion of the bar *j* and is flush therewith and projects downwardly, and the lower 40 end is formed in curved lines and united with the bar *b*.

Rounded pins *k* are mounted in the bars *j* and *f* which project outwardly as shown.

Having therefore described my new and 45 original design, what I claim is—

The herein described design for a halter loop substantially as shown.

JEREMIAH N. BULL.
